AUTOMATIC RINGLET CURLER

Nathan L. Solomon, New York, N. Y.

Application August 14, 1937, Serial No. 159,102

15 Claims. (Cl. 132—31)

The present invention has to do with curling hair and specifically deals with an improved and efficient curling device for readily forming ringlet curls. The object of the invention resides in 5 the provision of a clasp for initially clamping a strand or tress of hair and a removably rotatable key adapted to be projected into the clasp for curling the hair between the jaws of the clasp to form a ringlet curl. Other objects, advantages and features of the invention will appear from the following description considered in connection with the accompanying drawing in which:

Fig. 1 shows a view of the clasp according to 15 the invention attached to a strand or tress of hair before the latter is curled into ringlet formation.

Fig. 2 is a view of the clasp embracing a ringlet curl.

Fig. 3 is a longitudinal sectional view of the clasp along the line 3—3 of Fig. 2 but illustrating a removable key in part therein after having wound the tress grasped by the jaws.

Fig. 4 is a side view of the clasp shown in 25 Figs. 1—3.

Fig. 5 is a perspective view of the clasp shown in Figs. 1—4.

Fig. 6 is a perspective view of the detachable and rotatable key.

Fig. 7 is a plan view of a slightly modified clasp.

Fig. 8 is a side view of Fig. 7.

Fig. 9 is a plan view of a modified clasp, and

Fig. 10 is a side view of the clasp shown in 35 Fig. 9 associated with a removable key of the type shown in Fig. 6.

The ringlet curler according to the invention comprises a hair clasp C and a removable key K. The clasp includes complementary hair clamping jaws 10 and 11 having lugs 12 pivotally supported on fulcrum pin or shank 13 of rivet 14 which has its outer ends upset to prevent displacement along shank 13 of the normally diverged and reinforced manipulating portions 15 40 extending from the jaws.

Cooperating with the manipulating portions 15 are the outer terminals 16 of a coiled spring 17 having its inner end abutting fulcrum pin or shank 13. The action of terminals 16 is to normally hold the manipulating portions 15 diverged for holding the jaws closed as shown in Fig. 4.

Each of the jaws 10 and 11 of the clasp is provided with a centrally arranged aperture or opening 18 which removably receive a reduced 50 bifurcated depending portion 19 of the member

or key K, the arrangement being such that when a strand or tress of hair is interposed between and clamped by the jaws of the clasp, as shown in Fig. 1, a portion of the tress is accessible and disposed across the aligned openings 18.

The reduced depending part or fork 19 of the key is then inserted into one of the openings 18 and over the portion of the tress traversing these openings whereby the legs 20 of fork 19 straddle the exposed and accessible part of the tress 10 which serves as the origin of the ringlet curl to be formed.

The upper expanded part 21 of key K forms with the reduced fork 19 an annular stop shoulder 22 which limits the insertion of the fork 19 15 into the aligned openings 18, the inner faces of which serve as annular bearings to guide the rotational displacement of the fork at a time when the handle 24 is rotated.

During such rotation, the tress, now straddled 20 and grasped by the fork, starts to wind about the reduced fork 19, thus translating the formerly relatively straight tress held under slight compression between the jaws of the clasp into a plurality of successive convolutions. In other words, 25 the reduced fork winds the tress but always against the resistance of the pressure imparted by the perforated jaws due to the action of the coiled spring 17.

Having completely wound up the tress between 30 the jaws, the reduced fork is removed from the sides of the ringlet curl now formed between the jaws and from the aligned openings or bearings of the latter. This may be conveniently accomplished by applying an outward thrust to the 35 handle 24 of the key.

With the key removed from the jaws of the clasp, the ringlet curl formed is left therein under pressure created by the jaws due to the action of the coiled spring. To remove the ringlet 40 curl, the operator merely moves the manipulating portions of the clasp towards each other, thus separating the jaws and the latter may be readily removed from sides of the formed ringlet curl which now sustains itself in form without 45 requiring external support.

In the embodiment of the clasp according to Figs. 7 and 8, the jaws 10 and 11 thereof are bowed, that is, these jaws have convex surfaces facing each other and projecting from these surfaces are a plurality of radially but spaced ribs 23 emanating from the circumferential edges of openings 18 of each jaw. The object of these ribs is to prevent accidental displacement of the ringlet curl after it has been formed between 50 55

the jaws. In other aspects the embodiment according to Figs. 7 and 8 is along the lines of the form illustrated in Figs. 1-4 inclusive and is utilized in a similar fashion in connection with a key of the type shown in Fig. 6.

In the embodiment shown in Figs. 9 and 10, the clasp is in the form of a one piece U shaped loop of sheet metal having jaws or arms 10 and 11 integrally merged to a U shaped bend or elastic joint 25. Each of these jaws also includes a free outwardly extending terminal 26 or lip to facilitate the insertion of a tress of hair into the clasp. The inherent resiliency in the bend 25 tends to hold jaws 10 and 11 closed, for example, as shown in Fig. 9. In similar fashion, the construction according to Figs. 9 and 10 cooperates with a key K of the type shown in Fig. 6.

While I have described my invention in detail and have referred to specific applications thereof, I do not intend that the several embodiments herein disclosed shall be limited to such specific applications, but intend that all matter contained in the above description and shown in the accompanying drawings shall be interpreted as illustrative and not in a limiting sense.

I claim:

1. In combination, opposed and separable jaws defining a clasp for clamping a tress of hair, and key means disposed substantially normal to said jaws and removably projectable into at least one of the latter to grasp a portion of said tress interposed between said jaws for curling said tress.
2. In combination, opposed and separable pivotally interconnected jaws defining a clasp adapted to removably grasp a tress of hair, and key means adapted to be mounted on said clasp for grasping a portion of said tress to wind the latter in said clasp.
3. In combination, a clasp having opposed, separable, and bowed jaws for removably grasping a tress of hair, and key means removably mounted on said clasp and adapted to grasp a portion of said tress to wind said portion between said jaws.
4. In combination, a clasp having juxtaposed and opposing jaws for removably grasping a tress of hair, key means removably mounted on said clasp and adapted to grasp a portion of said tress to wind said tress between said jaws, and spring means for compressing the tress wound between said jaws.
5. In combination, a clasp having juxtaposed and separable jaws for grasping a tress of hair and including means for exposing a portion of said tress interposed between said jaws, and means for grasping said portion to wind said tress about said portion to form a ringlet curl.
6. In combination, a clasp having juxtaposed and separable jaws for removably grasping a tress of hair and including means for exposing a portion of said tress, and a key adapted to be mounted on said clasp and having a forked part adapted to straddle said exposed portion to wind said tress about said portion to form a ringlet curl.
7. In combination, a clasp having juxtaposed and separable jaws for removably grasping a tress of hair and having bearing means adapted to expose and render accessible a portion of said tress between said jaws, a key rotatively

guided by said bearing means and having means adapted to straddle said accessible portion of said tress to roll the latter about said accessible portion, and spring means for resisting separation of said jaws during rotation of said key.

8. In combination, a clasp having juxtaposed and separable jaws for removably grasping a tress of hair and including bearing means adapted to expose and render accessible a portion of said tress between said jaws, a key rotatably guided by said bearing means and including means adapted to removably straddle said accessible portion of said tress to roll the latter about said accessible portion to form a plurality of convolutions, and spring means cooperating to compress said convolutions during rotation of said key relative to said jaws.

9. In combination, a clasp having pivoted juxtaposed and separable jaws for removably grasping a tress of hair and including aligned openings for rendering accessible a portion of said tress interposed between said jaws, a rotatable member having a fork adapted to be removably inserted in and rotatably guided by said openings to straddle said accessible portion, said fork upon rotation of said member causing said tress to roll up about said accessible portions to form a plurality of convolutions, and spring means to resist separation of said jaws during rotation of said member and for compressing said convolutions.

10. In combination, a clasp having pivoted and separable jaws for removably grasping a tress of hair and including aligned openings for rendering accessible a portion of said tress interposed between said jaws, a rotatable member having a fork adapted to be removably inserted in and rotatably guided by said openings to straddle said accessible portion, said fork upon rotation of said member causing said tress to roll up about said accessible portion to form a plurality of convolutions, manipulating portions extending from said jaws, and spring means cooperating with said manipulating portions to resist separation of said jaws during rotation of said member and sustain said convolutions under pressure between said jaws.

11. The combination according to claim 10 wherein said member comprises an upper expanded part constituting a handle and a depending part constituting said fork.

12. The combination according to claim 10 wherein said rotatable member includes means to limit the insertion thereof into said clasp.

13. In combination, opposed, juxtaposed and separable jaws defining a clasp for gripping hair, and a key disposed substantially normal thereto and adapted to grasp a portion of said gripped hair to wind the latter about said gripped portion to form a plurality of successive convolutions during rotation of said key.

14. The combination according to claim 13 characterized in that said clasp includes bearing means for guiding the rotational displacement of said key and includes a plurality of ribs to prevent slippage of said convolutions formed within said clasp.

15. In combination, a clasp having bowed and separable arms adapted to grasp a tress of hair, and a key insertable in said clasp to wind said tress between said arms.

NATHAN L. SOLOMON.
